(57) **CLAIM**

The ornamental design for an electronic thermometer with wireless communication device, as shown and described.

DESCRIPTION

FIG. 1 is a front, top, and left side perspective view of an electronic thermometer with wireless communication device, showing our new design;

FIG. 2 is a rear, bottom, and left side perspective view thereof;

FIG. 3 is a front view thereof;

FIG. 4 is a rear view thereof;

FIG. 5 is a top view thereof;

FIG. 6 is a bottom view thereof;

FIG. 7 is a right side view thereof;

FIG. 8 is a left side view thereof;

FIG. 9 is an enlarged view of the circumscribed area IX in FIG. 1; and,

FIG. 10 is a front, top, and left side perspective view of the left portion thereof, shown at an enlarged scale.

The dot-dot-dashed broken lines in FIGS. 1 and 9 circumscribe the enlarged views and form no part of the claimed design.
